UNITED STATES PATENT OFFICE.

JULIEN F. CULLEN, OF PORTLAND, OREGON, ASSIGNOR TO COLUMBIA TIRE CORPORATION, OF PORTLAND, OREGON, A CORPORATION OF OREGON.

DESIGN FOR A TIRE.

Application filed March 5, 1924. Serial No. 8,843. Term of patent 3½ years.

To all whom it may concern:

Be it known that I, JULIEN F. CULLEN, a citizen of the United States, residing at Portland, in the county of Multnomah and State of Oregon, have invented a new, original, and ornamental Design for Tires, of which the following is a specification, reference being had to the accompanying drawings, forming a part thereof.

Figure 1 is a plan view of a portion of a tire, showing my new design, and,

Figure 2 is a transverse sectional view of same.

I claim:

The ornamental design for a tire as shown.

JULIEN F. CULLEN.
